CIGARETTE LIFTING MEANS FOR
CIGARETTE PACKS

Harold J. Gearin, Portland, Oreg.

Application May 1, 1934, Serial No. 723,297
Renewed March 3, 1936

1 Claim. (Cl. 206—56)

In opening a cigarette package considerable difficulty is usually experienced in lifting out the first cigarettes. This is due to the tightness of the pack, and frequently the first cigarettes withdrawn become more or less mutilated.

The object of my invention is to accomplish the removal of the first cigarettes by lifting them above the rest in the pack by the aid of a flexible strip of material of suitable tensile strength; 10 the strip being arranged within the package so as to extend under the cigarettes adjacent one wall of the pack with one end of the strip disposed between the cigarettes and a wall of the pack-wrapping so that when a portion of the top 15 of the wrapping has been broken away, the end of the strip may be readily seized, and, by being pulled up, will lift some of the cigarettes above the remainder of the pack so that the lifted cigarettes may be readily removed.

20 By the term pack-wrapping is to be understood the tinfoil, plain paper and waxed paper or cellophane, or similar materials, with which it is customary to enclose or wrap a group or pack of cigarettes to form a cigarette package.

25 The strip, in one embodiment of my invention, may be secured in place within the package with one end of said strip extending under the bottom of the cigarettes and thence up between the cigarettes and a wall of the pack-wrapping, said end, when released, being adapted to be extended a substantial distance above the top of the pack. Thus when the top of the pack-wrapping is broken away, this strip-end may be readily seized and pulled up, thus lifting some of the cigarettes 35 from the pack, as mentioned.

In another embodiment of my invention, the lifting strip is arranged to encompass both lateral sides and the bottom of the pack and the ends of the strip are doubled over on themselves under 40 the top of the pack-wrapping, each end of the strip being held in place by the pressure of the top of the pack-wrapping against the tops of the cigarettes, and when so arranged either side of the top of the pack-wrapping may be torn away 45 and the end of the strip there located released and operated for removing cigarettes, as mentioned.

In still another embodiment of my invention, lifting strips are fastened to inside end folds 50 of the bottom of the pack-wrapping and extend up between the inside of the corresponding end wall and the cigarettes to the top of the pack. With this arrangement of the lifting strips, it is possible to have interior pack-wrapper and lifting strips made all in one piece, as later explained,

offering simplicity and economy in construction.

The details of my invention are hereinafter fully described with reference to the accompanying drawings, in which:

Fig. 1 is a perspective drawing of an ordinary cigarette package with the pack-wrapping closed; 5

Fig. 2 shows a similar perspective view with a portion of the top of the wrapper torn away so as to release one end of the lifting strip, so that such end may be seized and operated as mentioned; 10

Fig. 3 shows a vertical diagrammatic longitudinal section of a lifting strip encompassing both lateral sides of the pack with the ends of the strip held in place by the pressure of the top of the pack against the top of the pack-wrapping; 15

Fig. 4 shows diagrammatically one modification in the arrangement of the lifting strip, with one end of the lifting strip secured in place at one lateral side of the pack and the other end of the strip arranged similarly as illustrated by Figs. 2 20 and 3;

Fig. 5 shows a perspective detail of the lifting strip, one end thereof being folded so as to be located above the pack and under the top of the pack-wrapping, the folded end also shown in broken line as extended for seizing and pulling up, and a broken line indicating where the strip would be cut if it is to be arranged as illustrated in Fig. 4; 30

Fig. 6 is a perspective diagram of a cigarette package, similar to Fig. 2, and illustrates a possible modification of my invention. As here illustrated, I employ two lifting strips, which, as shown by broken lines, are fastened to the folded 35 in ends of the interior wrapping at the bottom of the pack, one of the strip ends being shown as extending above the torn away top of the pack;

Fig. 7 is a fragmentary drawing of a portion of the cigarette package shown in Fig. 6 with the 40 freed end of the lifting strip shown pulled up and the adjacent cigarettes lifted above the others in the pack;

Fig. 8 shows the pack-wrapping and lifting strips of Fig. 6, with the wrapping unfolded and 45 opened out;

Fig. 8a is a fragmentary illustration of a portion of the pack-wrapping of Fig. 8 with one of the lifting strips attached; and

Fig. 9 is a drawing, on reduced scale, of the 50 interior pack-wrapping and lifting strips cut from a single sheet and ready for folding.

In the drawings, *a* represents the cigarettes placed in the pack-wrapping *b*. The pack-wrapping *b* has two broad, longitudinal flaps *c* and *c'* 55

and two narrow end flaps *n* and *n'* at the top and similarly two broad, longitudinal flaps *k* and *k'* and two narrow end flaps *o* and *o'* at the bottom. The lifting strips *d* or *d'* (Figs. 2, 3, 4, and 5) are located inside the pack-wrapping *b* adjacent to the sides and bottom of the pack of cigarettes.

One embodiment of my invention is shown in Fig. 4 where one end of the lifting strip *d* is secured to the inside of the side of the pack-wrapping *b* at *e*. The other end *f* of the lifting strip leads up to the top of the other side of the pack and is folded down upon itself. When the portion of the top of the pack-wrapping above the end *f* of the lifting strip is torn away, the said end *f* can easily be seized and pulled up, and in this way the cigarettes adjacent to the lifting strip are lifted sufficiently above the others in the pack so that they can easily be pulled out.

Figs. 3 and 5 illustrate another embodiment of my invention in which either end of the lifting strip may be pulled out. In these figures both the ends *g* and *g'* of the lifting strip *d'* extend around to the top of the pack and are folded down upon themselves. When one side of the top of the pack-wrapping is torn away, as at *h* in Fig. 2, and the corresponding end *g* of the lifting strip *d'* is pulled up, the other end *g'* of the lifting strip *d'*, which remains folded down upon itself, will be held in place between the tops of the cigarettes and the other side of the top of the pack-wrapping. Thus with this arrangement it is immaterial which side of the top of the cigarette package is opened first.

In Fig. 6 the lifting strips *e* and *e'* are fastened to the bottom sides of the narrow end folds *o* and *o'*, respectively, of the bottom of the pack-wrapping. In this construction of my invention it is necessary that the folds at the bottom of the pack-wrapping be so arranged that the narrow end folds *o* and *o'* are on top, that is next to the inside of the pack, and the broad, longitudinal folds or flaps *k* and *k'* placed below or outside of these. It can be readily seen that the pulling up of the lifting strips *e* or *e'* will pull up the narrow folds *o* or *o'* to which the lifting strips are attached and raise the adjacent cigarettes. The narrow folds *o* and *o'* in a way act as levers in aiding in the raising of the cigarettes and limit the extent to which the lifting strips can be pulled up. Fig. 7 shows the lifting strip *e'* pulled up and the adjacent cigarettes raised above the others in the pack as a result.

In Fig. 8 the pack-wrapping *b* has been unfolded and opened up. The front face of the wrapping of the pack shown in Fig. 6 and the adjacent upper and lower broad longitudinal folds or flaps *c* and *k* have been divided. *c'* and *k'* denote the other broad, longitudinal folds at top and bottom respectively, and the narrow end folds of the pack-wrapping are shown by *n* and *n'* at the top and *o* and *o'* at the bottom. The lifting strips *e* and *e'* are attached to the under or bottom sides of the folds *o* and *o'*, see Fig. 8a. These strips are then bent up at the lines *p* and *p'* and then bent in at the lines *q* and *q'* to cause the strip to remain adjacent the inside surfaces of the folds *o* and *o'* and the end faces of the pack-wrapping. 15

The lifting strips in Fig. 8 are separate pieces of material attached to the under side of the folds *o* and *o'*, as mentioned. However, it is not necessary for the lifting strips to be made of separate pieces in this way and attached to the pack-wrapping, for pack-wrapping and lifting strips can be cut from the same sheet with one operation and the lifting strips made integral with the pack-wrapping. This is illustrated in Fig. 9 which shows, on a reduced scale, the pack-wrapping *b'* and lifting strips *f* and *f'* cut from a sheet and ready for folding on the dotted lines. The possibility of this one-piece construction of my invention I consider as one of its most valuable features, because it is obvious that only a 30 very simple and inexpensive manufacturing operation is required for its adoption.

I claim:

In a cigarette package comprising a box-like wrapping formed of a sheet having its upper and lower portions folded over the top and the bottom of the pack of cigarettes, cigarette lifting means consisting of a strip of flexible material connected to a bottom fold of the wrapping at one wall and thence folded back up and over said fold and under the adjacent cigarettes seated thereon, and thence extended up between said wall and adjacent cigarettes, the upper end of said strip constituting a foldable tab adapted to be seized for pulling up the strip, whereby to lift the fold- 45 portion of the wrapping to which it is attached, and thus cause the cigarettes seated on such fold portion to be projected above the top of the pack.

HAROLD J. GEARIN. 50
